UNITED STATES PATENT OFFICE.

HIRAM PERCY MAXIM, OF PITTSBURG, PENNSYLVANIA.

VEHICLE-BRAKE.

SPECIFICATION forming part of Letters Patent No. 757,940, dated April 19, 1904.

Application filed June 13, 1903. Serial No. 161,250. (No model.)

To all whom it may concern:

Be it known that I, HIRAM PERCY MAXIM, a resident of Pittsburgh, in the county of Allegheny and State of Pennsylvania, have invented a new and useful Improvement in Vehicle-Brakes; and I do hereby declare the following to be a full, clear, and exact description thereof.

My invention relates to vehicle-brakes, and more especially to brakes wherein the brake-shoe is an expanding ring.

One of the objects of my invention is to so support or anchor the braking-ring that the strains will not produce a twisting on the vehicle-springs, but will be transmitted to the axle in the form of an approximately vertical load.

A further object of my invention is to so support a brake-shoe of expanding-ring type that said ring when released will move straight inwardly, so as to clear the brake-drum on all sides.

In vehicles provided with brake-shoes formed as an expanding ring working on a brake-drum the braking strains are usually very severe, and in most arrangements of such brakes these braking strains produce a twisting strain on the vehicle-springs which is very objectionable. The principal object of my invention is to prevent this twisting strain on the vehicle-springs, and to this end the support for the brake-shoe is so arranged that the strain is transmitted to the axle in the form of an approximately vertical load, so that the springs are not concerned in the braking strain at all.

In most brakes of the expanding-ring type in use up to the present time the ring tends to sag or drop down when released from the brake-drum, so that it will not be clear of the drum on the lower side.

A further object of my invention is to so support the brake-ring that when the latter is released from the brake-drum it will move straight inwardly, and thus clear the drum at the bottom as well as at the top.

In the accompanying drawings, Figure 1 is a side view of a motor-vehicle, showing my

brake applied thereto; and Fig. 2 is a plan view of the same.

In the drawings I have shown a motor-vehicle with a motor-suspending arrangement such as described and claimed in my application filed June 13, 1903, Serial No. 161,249.

In the drawings the vehicle-body is shown at 1, the axle at 2, the wheel at 3, and the springs at 4. Each of these parts may be of the usual or any preferred construction. The motor 5 is suspended according to my invention aforesaid—that is, it is suspended from the body of the vehicle by means of a hinge-joint 6—and in order to keep the connecting-gearing between the same and the vehicle-wheel in proper mesh it is held at approximately a uniform distance from the center of the wheel, this being accomplished by means of the distance-rod 7, which is hinged at its inner end to a clip 8, secured to the vehicle-axle, and at its outer end to the motor-bushing. The gearing between the motor and the vehicle is of the sprocket-and-chain type, comprising a chain 9, running over a sprocket-pinion on the motor and also over a sprocket-wheel 10, connected to the vehicle-wheel. The sprocket-wheel 10 is of comparatively large diameter, and the brake-shoe, which is in the form of a ring 11, is applied to the inside of the rim of said sprocket-wheel. Said brake is therefore applied as close as possible to the rim of the vehicle-wheel itself, which is very advantageous for the reason that said brake-shoe acts on a large radius, thus making the braking action very efficient.

The ends of the brake-ring are connected, by means of links 13, to a swinging lever 14, so that when the latter is turned in one direction it, together with the links 13, acts as toggles to expand the ring 11 against the braking-surface on the inside of the sprocket-wheel. The swinging lever 14 is secured to a short rock-shaft 15, to which is connected an arm 16, and the latter has connected thereto a rod 17, which runs to the foot-lever or other means for operating the brake.

The straightening of the toggles brings the brake-ring into contact with the brake-drum,

and this necessarily produces a very severe strain, which in prior brakes of this character has been transmitted to the vehicle-springs, producing a twisting strain therein. With my arrangement this is entirely overcome, as the support for said ring—namely, the rock-shaft 15—is so mounted that the strains are transmitted to the axle. Various ways of mounting this support may be employed to secure this effect, but with the motor arrangement shown this support is conveniently secured by mounting the rock-shaft 15 on the distance-rod 7. Inasmuch as this distance-rod is supported at one end from the axle and at its opposite end from the motor-casing, which in turn is connected to the body of the vehicle, the strain due to the braking of the vehicle can in no manner affect the vehicle-springs; but said strain is transmitted to the vehicle-axle in the form of approximately a vertical load. Such a load the axle is well adapted to bear, and the springs are left entirely free to perform their normal functions and are also relieved of much liability of breakage, which has occurred with former devices of this kind. In order to keep the brake-band 11 from sagging, so as to rest against the brake-drum when released, I provide a supporting-arm 20, secured to the distance-rod 7 and extending around the axle to the opposite side of the brake-ring. The outer end of this supporting-arm is reduced in diameter and projects loosely into an opening formed in a lug 21 on the brake-ring. The brake-ring therefore is supported at approximately two diametrically opposite points—that is, at the point 21 and on the rock-shaft 15. The end of the arm 20 fits loosely in the opening in the ring and projects practically radially of said ring, so that the reduction of the diameter of the ring, which occurs when it is released from the drum, causes it to move forward on said arm, thus insuring the brake-ring moving inwardly in all directions and clearing the same from the brake-drum on all sides. As a consequence the brake-drum is entirely relieved of the friction of the ring except when it is desired to apply the latter thereto. The sprocket-wheel 10 is connected to the wheel-spokes by detachable clips 22. My improved brake can be applied to vehicles of all kinds and not merely to motor-vehicles such as shown; it merely being necessary to support the brake-ring—that is, the rock-shaft 15—from suitable rods or the like hinged to the vehicle-axle and vehicle-body, preferably two such rods being used, one taking the place of the motor-casing 5 and the other of the distance-rod 7. Vehicles other than motor-vehicles which are not supplied with a sprocket-wheel can have a brake-drum attached to the wheel-spokes by means of detachable clips, such as are shown for attaching the sprocket-wheel thereto, and the brake-band will operate on this drum.

By means of my brake the braking strain is applied as close as possible to the rim of the vehicle-wheel, so that it operates on a long radius and produces a very severe braking effect. The strains produced thereby, however, are transmitted directly to the axle of the vehicle, so that they can be easily taken care of, and the support for the ring is such that when released it is entirely free from the brake-drum on all sides.

What I claim as my invention, and desire to secure by Letters Patent, is—

1. In a motor-vehicle brake, the combination with the vehicle wheel and body, of a motor suspended from the body by a hinge connection, gearing between said motor and the wheel, means for holding said motor an approximately uniform distance from the wheel-axis, a brake rim or drum rotating with said wheel, an expanding ring arranged to engage said drum, means for expanding said ring, and an anchor for said ring supported from the motor.

2. In a vehicle-brake, the combination with the vehicle wheel and body, of a motor suspended from the body by a hinge-joint, a distance-rod hinged to said motor and to the vehicle-axle, a brake-drum arranged to rotate with said wheel, an expanding ring for engaging said drum, and a support for said ring connected to said distance-rod.

3. In a vehicle-brake, the combination with the vehicle wheel and body, of a motor suspended from the body by a hinge-joint, a distance-rod hinged to said motor and to the vehicle-axle, a brake-drum arranged to rotate with said wheel, an expanding ring for engaging said drum, a support for said ring connected to said distance-rod, and a second support for said ring engaging the same on the side opposite the first support.

4. In a vehicle-brake, the combination with the vehicle wheel and body, of a motor suspended from the body by a hinge-joint, a distance-rod hinged to said motor and to the vehicle-axle, a brake-drum arranged to rotate with said wheel, an expanding ring for engaging said drum, a support for said ring connected to said distance-rod, and an arm extending from said support and engaging the ring on the opposite side.

5. In a vehicle-brake, the combination with the axle and wheel, of a brake rim or drum rotating with the wheel, an expanding ring arranged to engage said rim, a support for said ring at the open side thereof, and a support on the opposite side of said ring with which said ring has a sliding connection.

6. In a vehicle-brake, the combination with the axle and wheel, of a brake rim or drum rotating with said wheel, an expanding ring arranged to engage said drum, means for supporting the open side of said ring from the vehicle-axle, and an arm extending from said

support to the opposite side of the ring and having a sliding connection therewith.

7. In a vehicle-brake, the combination with the axle and wheel, of a brake rim or drum rotating with the wheel, an expanding ring arranged to engage said drum, links connected to the open ends of said ring, a swinging lever to which said links are connected, a support from the vehicle-axle in which said lever is

mounted, and an arm connected to said support and extending to the opposite side of the ring with its end in sliding engagement therewith.

In testimony whereof I, the said HIRAM PERCY MAXIM, have hereunto set my hand.

HIRAM PERCY MAXIM.
